US00D771921S

(12) **United States Design Patent** (10) **Patent No.:** **US D771,921 S**
(45) **Date of Patent:** **** Nov. 22, 2016**

(54) **SHOE INSOLE**

(71) Applicant: **Spenco Medical Corporation**, Waco, TX (US)

(72) Inventors: **David B. Granger**, Lorena, TX (US); **Jacob Martinez**, Temple, TX (US)

(73) Assignee: **Implus Footcare, LLC**, Durham, NC (US)

(**) Term: **15 Years**

(21) Appl. No.: **29/531,425**

(22) Filed: **Jun. 25, 2015**

(51) LOC (10) Cl. **02-04**

(52) U.S. Cl.

USPC **D2/961**

(58) **Field of Classification Search**

USPC D2/896, 946, 947, 950, 951, 954, 955, D2/956, 961, 976, 948, 949, 953, 959, 960, D2/968

CPC A43B 7/14; A43B 7/1405; A43B 7/141; A43B 7/1415; A43B 7/142; A43B 7/1425; A43B 7/143; A43B 7/1435; A43B 7/144; A43B 7/1445; A43B 7/145; A43B 7/1455; A43B 7/1475; A43B 7/148; A43B 7/1485; A43B 7/149; A43B 7/1495; A43B 7/16; A43B 7/18; A43B 7/19; A43B 7/22; A43B 7/223; A43B 7/226; A43B 7/28; A43B 7/30; A43B 7/34; A43B 7/36; A43B 7/38; A43B 13/38; A43B 13/383; A43B 13/386; A43B 13/39; A43B 13/40; A43B 13/42; A43B 17/14; A43B 17/00; A43B 17/003; A43B 17/006; A43B 17/02; A43B 17/023; A43B 17/026; A43B 17/03; A43B 17/08; A43B 17/10; A43B 17/102; A43B 17/105; A43B 17/107; A43B 17/18; A43B 19/00

(57) **CLAIM**

The ornamental design for a shoe insole, as shown and described.

DESCRIPTION

FIG. 1 is a perspective view of a shoe insole showing our new design;

FIG. 2 is a bottom view of a shoe insole shown in FIG. 1; FIG. 3 is a top view of a shoe insole shown in FIG. 1; FIG. 4 is a medial side view of a shoe insole shown in FIG. 1;

FIG. 5 is a lateral side view of a shoe insole shown in FIG. 1;

FIG. 6 is a front side view of a shoe insole shown in FIG. 1; and,

FIG. 7 is a back side view of a shoe insole shown in FIG. 1.

1 Claim, 5 Drawing Sheets
